Application filed May 28, 1932. Serial No. 43,926. Term of patent 3½ years.

To all whom it may concern:

Be it known that I, ALFRED WEGNER, a citizen of the United States, residing at Chicago, in the county of Cook and State of Illinois, have invented a new, original, and ornamental Design for Emblem, of which the following is a specification, reference being had to the accompanying drawing, forming a part thereof.

The figure is a front view of an emblem, showing my new design.

The emblem in this case has no appreciable thickness.

I claim:

The ornamental design for an emblem, substantially as shown and described.

ALFRED WEGNER.
